Inventor
By William R. Baird, Secy.

UNITED STATES PATENT OFFICE.

MARIE LOUISE BÜCHLER WARD, OF LONDON, ENGLAND.

FINGER-PROTECTOR.

971,093.

Specification of Letters Patent. Patented Sept. 27, 1910.

Application filed March 20, 1909. Serial No. 484,754.

To all whom it may concern:

Be it known that I, MARIE LOUISE BÜCHLER WARD, a subject of the Emperor of Austria-Hungary, residing at London, in England, have invented certain new and useful Improvements in or Relating to Finger-Protectors, of which the following is a specification.

This invention relates to improvements in devices for protecting the fingers from cold.

According to this invention a number of caps or finger stalls singly or in groups are provided, each cap fitting on to the fingers and worn beneath an outer cover such as a glove.

The invention will be more clearly understood from the following description taken in connection with the accompanying drawings, in which:—

Figure 1 shows in elevation the back of a hand with devices according to one modification of this invention for protecting the fingers from cold. Fig. 2 is a perspective view of one of these devices from one side, and Fig. 3 a perspective view from the opposite side to that shown in Fig. 2; Fig. 4 shows an elevation of a device constructed according to another modification of this invention.

Like letters indicate like parts throughout the drawings.

Referring to Figs. 1 to 3, there is provided for each finger a cap A which is preferably made of paper. The cap A is provided with an extension or tab A' having on the side worn adjacent to the finger a gummed portion A². On the opposite side to the tab A' there is a V-shaped slit A³ for the purpose of permitting the fingers to be easily bent. The gummed portion A² is moistened before fixing the cap in position on the finger so that it is held in position.

The devices are intended to be worn beneath gloves and in Fig. 1 the glove is indicated by a broken line.

Referring to Fig. 4 caps or covers B are provided for each of the fingers but these instead of being separate as in Fig. 1 are

joined together and an extension B' is arranged to cover the back of the hand. The palm of the hand is not covered by the device. The end of the extension B' is provided with a gummed portion B² on the side adjacent to the wrist whereby it can be firmly fixed in position, as with the modification shown in Fig. 1, the device is intended to be worn beneath a glove and this is indicated by a broken line.

It will be obvious that this invention may be applied for covering the feet and toes, as well as the hands and fingers.

The caps or covers are preferably made of paper as mentioned above, but rubber or kid or other suitable material may be employed. Some fatty substance may or may not be added on the inside of these caps or covers.

In the case of using the caps to cover the fingers the caps may be permanently fixed in the gloves and sold in this form integral with the glove.

It is obvious that various other modifications may be made in carrying this invention into effect. For example, instead of the provision of a gummed portion for holding the caps or covers in position, other suitable means may be employed.

What I claim as my invention and desire to secure by Letters Patent is:—

1. A protector of the character described, consisting of a cover or stall substantially the full length of the finger, made of paper or like material of a somewhat stiff character, and having its inner end cut off at substantially a right angle to its axial line, the inner side of the stall being slitted from its inner end to a point beyond the second joint of the finger when the stall is in use, and a tab being provided, projecting from the rear side of the inner end opposite to the slit.

2. A protector of the character described, comprising a series of covers or stalls for the fingers, each having in the front inner edge thereof a V-shaped opening, and a tab, common to all of the covers, secured to the back inner edge thereof, substantially as described.

3. A protector of the character described,

comprising a series of covers or stalls for the fingers, each having in the front inner edge thereof a V-shaped opening, and a tab, common to all of the covers, secured to the back inner edge thereof, said common tab taking the form of a protector for the back of the hand.

In testimony whereof I have signed my name to this specification in the presence of two subscribing witnesses.

MARIE LOUISE BÜCHLER WARD.
